UNITED STATES PATENT OFFICE

LOUIS E. PERKINS, OF BROOKLYN, NEW YORK, ASSIGNOR TO PERKINS MARINE LAMP CORPORATION, OF BROOKLYN, NEW YORK, A CORPORATION OF NEW YORK

MARINE LAMP

Application filed April 17, 1931. Serial No. 530,750.

It is common to furnish marine lamps which may be illuminated by an electric current and a glow light or if this fails, by an ordinary kerosene burner. As such lamps must be in place, due to the electrical connections during the ordinary conditions of service, it is necessary to have access to the interior through a door, and as these lamps are placed against one or more surfaces, it is most convenient to have such access through a door, enclosing a lens and such is common practice. However, when this is done, a problem is presented, because of air leakage about the sides of the door, which seriously affects the kerosene lamp when burning and will either cause it to smoke or blow it out. When the lamp is functioning under severe conditions, such as during a storm, the object of my invention is to overcome this difficulty by making a peculiar air tight joint at each side of the door.

For a more detailed description of my invention, reference is to be had to the accompanying drawings, forming a part hereof in which

25 Figure 1 is a front elevation of one embodiment of my invention;

Figure 2 is a side elevation, partially in section of this structure; and

Figure 3 is a sectional view taken on the 30 lines 3—3 of Figure 1;

Throughout the various views of the drawings, similar reference characters designate similar parts.

My improved lamp 1 has the usual casing 2, with a bottom 3 and on this bottom are mounted the glow light support 4 and the reservoir 5 of the oil burner 6. An electric glow light 7 is mounted at the top of the support 4. All the foregoing parts may be conventional, and form no part of my invention.

The casing 2 has an opening in front, which is closed by a door 8 which contains a lens 9, mounted in the usual manner and secured in place with an air tight joint. The door 8 is hinged at one side at 10 and provided with

a beaded edge 11 at the other side, of the conventional kind. The frame is provided with a bead 12 which fills an interrupted part of the bead 11 when the door is closed, and a usual sliding bolt 13 passes through the parts 50 11 and 12 to hold the door locked under the usual conditions of service.

Adjacent to the hinges 10 and parts 11 and 12 are mounted the flange strips 14 which press close against the curved parts 10, 11 and 12, as indicated, so as to form a tight joint against these parts, when functioning. This joint is not absolutely tight but it is nearly so. It is found by experiment that when exposed to a high wind, a certain amount of 60 leakage will occur. These strips 14 are secured in place along with the hinges 10 on one side and the loop 12 on the other by means of suitable bolts 15.

At each side of the door are bolts 16 which carry the bands 17 at the top and bottom of the lens 9, and at the inner end of these bolts are secured Z-baffle plates 18, which have their inner ends fitting snug against the casing 2 of the lamp. These co-operate with 70 the exterior strips 14 to make a tight joint at each side of the door 8.

While I have shown and described one embodiment of my invention, it is obvious that it is not restricted thereto, but that it is broad 75 enough to cover all structures that come within the scope of the annexed claims.

Having thus described my invention, what I claim is:

1. In a device of the class described, a casing with a door opening, a hinge at one side of the said opening and a loop at the other, a door with a hinge part to engage the hinges on the casing, and with loops adapted to co-80 operate with the loops on the casing, strips with curved parts adapted to make a tight joint with the hinges and loops, and Z-irons carried on the interior of the door and adjacent to the exterior strips, the said Z-irons 85 90

adapted to engage the casing and co-operate in forming a tight joint.

2. In a device of the class described, a casing with a door opening, a door mounted in said opening, with hinges at one side and loops at the other, Z-irons at each side and secured to the interior of the door, said irons adapted to engage the interior of the casing so as to form an air tight joint in connection therewith when the door is closed.

In testimony whereof, I have hereunto set my hand this 31st day of March, 1931.

LOUIS E. PERKINS.
